UNITED STATES PATENT OFFICE

143,080

DESIGN FOR AN AUTOMATIC ACTUATOR FOR AIRPLANE WING FLAPS

William P. Lear, North Hollywood, and John M. Wehner, Culver City, Calif., assignors to Lear, Incorporated, Piqua, Ohio, a corporation of Illinois

Application January 6, 1945, Serial No. 117,294

Term of patent 14 years

(Cl. D71—1)

To all whom it may concern:

Be it known that we, William P. Lear and John M. Wehner, citizens of the United States of America, residing at North Hollywood, county of Los Angeles, State of California, and at Culver City, in the county of Los Angeles, in the State of California, respectively, have invented a new, original, and ornamental Design for an Automatic Actuator for Airplane Wing Flaps, of which the following is a specification, reference being had to the accompanying drawings, forming a part thereof.

In the drawings:

Fig. 1 is a top plan view of an automatic actu-

ator for airplane wing flaps, illustrating our new design.

Fig. 2 is a side elevational view of the actuator shown in Fig. 1.

Fig. 3 is a left end elevational view of the actuator shown in Fig. 1.

Fig. 4 is a right end elevational view of the actuator shown in Fig. 1.

We claim:

The ornamental design for an automatic actuator for airplane wing flaps, substantially as shown.

WILLIAM P. LEAR.
JOHN M. WEHNER.
